(57) **CLAIM**

The ornamental design for a vehicle and/or replica, as shown and described.

DESCRIPTION

FIG. 1 is a left, front perspective view of a vehicle and/or replica showing my new design;

FIG. 2 is a right, rear perspective view thereof;

FIG. 3 is a right, rear perspective view thereof;

FIG. 4 is a left, rear perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines shown throughout the drawing views represent portions of the vehicle that are for environmental and illustrative purposes that form no part of the claimed design.
